UNITED STATES PATENT OFFICE.

ERASTUS E. WINKLEY, OF LYNN, AND HERMAN A. DAVENPORT, OF BROCKTON, MASSACHUSETTS, ASSIGNORS TO UNITED SHOE MACHINERY CORPORATION, OF PATERSON, NEW JERSEY, A CORPORATION OF NEW JERSEY.

MANUFACTURE OF SHOES.

Application filed August 5, 1925. Serial No. 48,386.

This invention relates to the manufacture of shoes, and has more particular reference to the application of compacting or shaping pressure to the bottoms of shoes. In certain 5 important aspects the invention is especially applicable to the manufacture of welt shoes, while in other aspects it is not thus limited but is generally applicable to the manufacture of shoes of various kinds.

10 In the manufacture of many kinds of shoes, especially women's shoes of the lighter grades, it is generally recognized as desirable to produce what is termed a "close edge" effect,—that is, to shape the bottom of the 15 shoe in such manner that the margin or edge of the sole (including the welt in the case of a welt shoe) will lie close to the upper, with as narrow a crease between these parts as it is practicable to form. In the 20 manufacture of welt shoes it has proved to be difficult, if not impossible, to produce as close an edge as in turn work, because of the fact that the materials which are fastened together by the inseam, even when trimmed 25 as closely as possible to the inseam stitches, form a ridge or projection which tends to hold the margin of the outsole away from the upper. There is also usually found at each end of the inseam a pucker in the edge 30 of the upper, which forms a projection that contributes to the same effect and that sometimes also renders the bottom of the outsole uneven so that the heel will not fit the outsole closely at the breast line. It has proved 35 to be impossible to remedy these conditions entirely by the operation of leveling the outsole, even when supplemented by the well known operation of beating the margin of the sole in the shank, since after the outsole 40 has been secured to the welt it acts as a binder to hold the materials which project at the inseam from spreading freely under the leveling pressure. As an alternative, it has been proposed to flatten the projecting 45 materials sufficiently for the purpose in view before the outsole is applied, either by the use of a hammer or by the action of a roll such as used in sole-leveling machines. A manual operation such as that involved 50 in hammering the projecting materials is slow and expensive and non-uniform in its results, and must also be performed with much care to avoid damage to the shoe. It

has been found, furthermore, that in the use of rolling pressure, especially with machines of the automatic type, there is also serious danger of damage to the shoe by overstraining the inseam, particularly in the case of comparatively light materials such as are commonly used in women's shoes.

The present invention provides a method of treating welt shoes whereby the materials projecting at the inseam may be flattened uniformly and to such an extent as is necessary to facilitate the formation of the desired close edge and the close fit of the heel, without danger of damaging the shoe even when made of light materials. In accordance with this method, in one important aspect, there is applied to the bottom of the shoe, after the welt-sewing operation, and preferably also after the inseam-trimming operation, a piece of flexible material, herein frequently termed a saddle, and through this material flattening or compacting pressure is applied to the shoe bottom to prepare the shoe for the reception of the outsole. For the best results the flexible material should be of sufficient toughness to prevent any substantial indentation thereof by the inseam projection, and it should also be flexible enough to conform readily to the shape of the shoe bottom. It has been found that Indian-tanned leather meets these requirements, the leather being preferably placed so that its tougher flesh side is toward the bottom of the shoe. It is advantageous also to apply to the flexible material or saddle a pull at each side in the direction of the height of the shoe to hold it tightly against the shoe bottom during the application of the pressure. By the use of this method there may advantageously be utilized, in the treatment of shoes preparatory to the application of the outsole, machines of the type used heretofore to apply rolling pressure automatically for leveling the outsole, since the interposed flexible material has a cushioning effect which prevents damage to the shoe by the comparatively heavy rolling pressure applied by such machines.

In a further important aspect, the invention provides novel means adapted for use in applying pressure to the bottoms of shoes, including a novel saddle constructed and arranged to facilitate the proper application

of such pressure. For uniformity in the pressure-applying operation, it is desirable, as above intimated, that the saddle substantially conform, or be readily conformable, to the curvature of the bottom of the shoe, and the invention accordingly provides a saddle which is formed to present toward a portion of the bottom of the shoe a face which is concave in the direction of the length of the shoe, thus adapting it for effective use at the forepart of the shoe. A saddle so formed is particularly well adapted for use where, as herein shown, the saddle is subjected at each side of the forepart at the rear of the toe to a pull in the direction of the height of the shoe, by the force of which the saddle, if not concaved lengthwise of the forepart, would be held with its front end spaced more or less from the toe of the shoe. As herein illustrated, the saddle is formed in the desired shape by providing therein slits extending lengthwise of the shoe along the portions at the opposite sides of the forepart, and by shortening the marginal portions lying between said slits and its side edges so as to contract the periphery of the saddle. Conveniently also the slits are so formed as to provide flaps adapted to be engaged in tensioning the saddle over the shoe. A further advantage in the use of a saddle thus provided with a concavity to receive the shoe is that it is comparatively easy to position the saddle in the proper location upon the shoe. It has been found, furthermore, that when constructed as above described, the same saddle may be used in operating upon shoes of various sizes.

While the invention is herein illustrated with particular reference to its use in applying pressure to the bottom of a welt shoe prior to the application of the outsole to the shoe, the invention in various novel aspects is not thus limited, since a saddle formed as herein shown and described is likewise well adapted for use in applying sole-leveling pressure to shoes of various kinds including both welt and turn shoes.

The invention will now be more particularly described by reference to the accompanying drawings and thereafter pointed out in the claims.

In the drawings—

Fig. 1 is a partial side elevation of a machine adapted for use in practising the method of this invention.

Figs. 2 and 4 show the toe and heel ends of a welt shoe before the seam rolling operation.

Figs. 3 and 5 show the same after the seam rolling operation.

Fig. 6 is an enlarged detail of the saddle.

The machine shown is of the same general type as that shown and described in various prior United States Letters Patent, including Patent No. 1,239,664 granted on Septem-

ber 11, 1917, upon an application of W. C. Baxter, and as much of the mechanism as is common to prior machines will therefore be only briefly described herein.

The shoe 10 to be treated is jacked on a heel post 12 and a toe post 14, which are rocked as a whole about a pivot at 16, so as to oscillate beneath a heavily spring-pressed roll 18, carried on an arm 20, pivoted at the rear of the machine, by suitable power mechanism, for description of all of which reference may be made to the prior patents.

The novel saddle 22 of the present invention is connected by two springs 24, 26 on each side to a lever 28 pivoted on the toe post and locatable in any desired position by means of the segment 30. The saddle shown is made preferably of Indian-tanned leather (which is a species of oil tanned rawhide believed to be manufactured in accordance with the aboriginal methods of preparing leather in America), and has its flesh side toward the shoe. Such leather is flexible enough to conform readily to the contour of a shoe, and is at the same time sufficiently tough on its flesh side for the purpose in view. The saddle is provided, at the rear of its center, or at the shank of the shoe, with an ear 32 on each side, to which a spring 24 is fastened. Its forward portion is slit at each side at 34, the slits extending lengthwise of the saddle, and the marginal portions or straps 36 thus formed at each side are shortened by the removal of a short piece and the resulting ends are fastened together by plates 38. The slits 34 are preferably curved, as shown, to provide flaps, and to these flaps the springs 26 are attached by plates 39. The shortened straps pull the forepart of the saddle into a longitudinally concave shape, contracting its periphery, as shown, so that when the springs 26 are drawn down by the lever 28 the toe end of the saddle as well as other portions will fit over and pull down on the bottom of a shoe in the machine. The saddle shown is long enough to cover the entire shoe bottom. Preferably the straps 36 are positioned outside of the flaps formed by the slits 34.

Figs. 2 and 4 show the ends of a shoe bottom after the inseam-trimming operation. The upstanding ridge or projection 40 along the inseam and the pucker or projection 42 in the upper at the heel seat are shown. These projections in the finished shoe, if left as they are, will hold the insole and the outsole apart to such an extent as to render it very difficult, if not impossible, to obtain the desired close edge effect between the margin of the outsole and welt and the upper. The conditions cannot be adequately remedied by leveling the outsole, because after the outsole stitching operation the projection at the inseam is held so firmly in position that it cannot be satisfactorily flattened out.

It has been proposed, as an alternative, to place the shoe, after the inseam trimming operation, in a machine such as utilized heretofore for leveling outsoles by rolling pressure, and to roll down the projections with the leveling roll. It has been found, however, that in this operation there is serious danger of straining the inseam or of otherwise damaging the shoe, especially in the case of shoes that are made of light materials, such as women's shoes. In accordance with our invention, this difficulty is avoided by interposing a layer of tough flexible material, for example a saddle such as hereinbefore described, between the shoe and the pressure applying means. It is preferable that the saddle be made of such material that the inseam projection cannot indent it to any substantial extent, and we have found that the flesh side of leather suitable for saddles is better for engagement with the shoe than the grain side, since it is tougher.

The machine shown, including a saddle such as shown and described, is useful also in all respects as a sole leveling machine and may well be so used on the same shoes after the attachment of the outsole, greatly improving the production of a close edge around the entire shoe forward of the heel. The saddle can, if desired, be turned wrong side out to bring the smoother surface of the grain side of the leather against the tread surface of the outsole. The described saddle effects a strong downward pull over the toe end of the shoe as well as at the sides, due to the longitudinal concavity described, and thus the desired effect is secured at the toe as well as at the sides of the forepart. The longitudinal concavity of the saddle shown also prevents it from slipping lengthwise of the shoe and the tension at its sides prevents lateral displacement while assisting in compacting or flattening the shoe materials.

While we have shown the saddle as made of leather, any material having the requisite toughness can be used. We have found Indian-tanned leather perfectly successful in both leveling and rolling down seams.

When welt shoes are treated in the manner hereinbefore described, the usual filler between the outsole and the insole may be entirely dispensed with at the ball portion of the shoe. This brings the outsole at this portion of the shoe closer to the wood of the last than where a filler is interposed and thus facilitates the shaping of the outsole to the contour of the bottom of the last.

Having described our invention, what we claim as new and desire to secure by Letters Patent of the United States is:—

1. That improvement in methods of making welt shoes which consists in applying a piece of flexible material to the bottom of a shoe after the welt sewing operation and before the outsole is applied to the shoe, and

operating through said flexible material to apply compacting pressure to the bottom of the shoe:

2. That improvement in methods of making welt shoes which consists in applying to the bottom of a shoe, after the welt sewing operation and before the outsole is applied to the shoe, a piece of flexible sheet material, such as leather, of sufficient toughness to prevent any substantial indentation thereof by the shoe materials projecting at the inseam, and operating through said flexible material to flatten said projecting shoe materials.

3. That improvement in methods of making welt shoes which consists in applying to the bottom of a shoe, after the welt sewing operation and before the outsole is applied to the shoe, a piece of Indian-tanned leather with its flesh side toward the shoe, and operating through said leather to apply compacting pressure to the bottom of the shoe.

4. That improvement in methods of making welt shoes which consists in applying a piece of flexible material to the bottom of a shoe after the welt sewing operation and before the outsole is applied to the shoe, and applying to said flexible material rolling pressure to compact the materials on the bottom of the shoe.

5. That improvement in methods of making welt shoes which consists in sewing a welt to a shoe, trimming the inseam, thereafter prior to the application of the outsole applying to the bottom of the shoe a piece of leather with its flesh side toward the inseam, and applying rolling pressure to said leather to flatten the shoe materials projecting at the inseam.

6. That improvement in methods of making welt shoes which consists in applying a piece of flexible sheet material to the bottom of a shoe after the welt sewing operation and before the outsole is applied to the shoe, pulling upon said flexible material in the direction of the height of the shoe to hold it tightly against the bottom of the shoe, and while thus pulling upon the flexible material applying pressure to said material to flatten the shoe materials projecting at the inseam.

7. That improvement in methods of making welt shoes which consists in applying to the bottom of a shoe, after the welt sewing operation and before the outsole is applied to the shoe, a saddle extending along the shank and forepart of the shoe, pulling upon said saddle at the opposite sides of the shank and of the forepart in the direction of the height of the shoe to hold the saddle tightly against the bottom of the shoe, and while thus pulling upon the saddle applying thereto rolling pressure to compact the materials on the bottom of the shoe.

8. In a machine of the class described, the combination with a shoe support and

- means for applying compacting pressure to the bottom of a welt shoe on said support after the welt sewing operation and before the outsole is applied to the shoe, of a saddle comprising a piece of leather arranged to be interposed between said pressure applying means and a portion at least of the bottom of the shoe and having its flesh side toward the shoe.
9. In a machine of the class described, the combination with a shoe support and a roll relatively movable to apply rolling pressure to the bottom of a welt shoe on said support after the welt sewing operation and before the outsole is applied to the shoe, of a saddle comprising a piece of Indian-tanned leather arranged to be interposed between said roll and the shank and forepart of the shoe and having its flesh side toward the shoe.
10. In a machine of the class described, the combination with a shoe support and means for applying compacting pressure to the bottom of a shoe on said support, of a saddle of flexible material arranged to be interposed between said pressure applying means and the bottom of the shoe, said saddle being so formed as to present toward a portion of the bottom of the shoe a face which is concave in the direction of the length of the shoe.
11. In a machine of the class described, the combination with a shoe support and means for applying compacting pressure to the bottom of a shoe on said support, of a saddle of flexible material arranged to be interposed between said pressure applying means and the bottom of the shoe at the shank and the forepart of the shoe, said saddle being formed to present toward the bottom of the forepart of the shoe a face which is concave in the direction of the length of the shoe.
12. In a machine of the class described, the combination with a shoe support and means for applying compacting pressure to the bottom of a shoe on said support, of a saddle of flexible material arranged to be interposed between said pressure applying means and the bottom of the forepart of the shoe, said saddle being formed to present to the bottom of the shoe at the forepart a face which is concave in the direction of the length of the shoe, and means for applying to the saddle at each side of the forepart of the shoe a pull in the direction of the height of the shoe.
13. In a machine of the class described, the combination with a shoe support and means for applying compacting pressure to the bottom of a shoe on said support, of a saddle of flexible material arranged to be interposed between said pressure applying means and the bottom of the forepart of the shoe, said saddle having slits formed therein along its opposite side portions to provide flaps extending beyond the sides of the forepart of the shoe and having its marginal portions between said slits and its side edges shortened to form a concavity to receive the shoe, and means attached to said flaps for 70 tensioning the saddle in the direction of the height of the shoe.
14. In a machine of the class described, the combination with a shoe support and means for applying compacting pressure to the bottom of a shoe on said support, of a saddle of flexible material arranged to be interposed between said pressure applying means and the bottom of the shoe at the shank and the forepart of the shoe, said saddle being shaped to present toward the bottom of the forepart of the shoe a face which is concave in the direction of the length of the shoe, and means attached to the opposite sides of said saddle at the shank 80 and the forepart for tensioning the saddle in the direction of the height of the shoe.
15. For use in a machine of the class described, a saddle of flexible sheet material adapted to cover the bottom of the forepart of a shoe, said saddle having slits formed therein along its opposite sides and having its marginal portions between said slits and its side edges shortened to concave the saddle lengthwise of the shoe.
16. For use in a machine of the class described, a saddle of flexible sheet material adapted to cover the bottom of the forepart of a shoe, said saddle having curved slits formed therein along its opposite sides to provide flaps adapted to be engaged for holding the saddle on the shoe and having its marginal portions between said slits and its side edges shortened to produce a concavity to receive the shoe.
17. For use in a machine of the class described, a saddle of flexible sheet material adapted to cover the bottom of the forepart of a shoe, said saddle having slits formed therein along its opposite sides to provide flaps adapted to be engaged for holding the saddle on the shoe and having outside of said flaps strap portions which are shortened to contract the peripheral edge of the saddle.
18. For use in a machine of the class described, a saddle of flexible sheet material adapted to be applied to the bottom of a shoe and so formed as to present toward a portion of the bottom of the shoe a face which is concave in the direction of the length of the shoe.
19. For use in a machine of the class described, a saddle of flexible sheet material adapted to cover the bottom of the shank and forepart of a shoe and having its forepart formed to present toward the bottom of the shoe a face which is concave lengthwise of the shoe.
20. For use in a machine of the class described, a saddle of flexible sheet material

adapted to be applied to the bottom of the forepart of a shoe and having its peripheral edge shortened to produce a concavity to receive the shoe.

21. For use in a machine of the class described, a saddle of Indian-tanned leather adapted to cover the bottom of the shank and forepart of a shoe with its flesh side toward the shoe and having the peripheral edge of its forepart shortened to produce a concavity to receive the shoe.

22. That improvement in methods of making welt shoes which consists in applying a piece of flexible material to the forepart of a shoe after the welt sewing operation and before the outsole is applied to the shoe, and operating through said flexible material to apply compacting pressure to the bottom of the shoe.

23. That improvement in methods of making welt shoes which consists in applying a piece of flexible material to the forepart and shank of a shoe after the welt sewing oper-

ation and before the outsole is applied to the shoe, and applying to said flexible material 25 rolling pressure to compact the materials on the bottom of the shoe.

24. In a machine of the class described, the combination with a shoe support and means for applying compacting pressure successively to different portions of the bottom of a shoe on said support, of a saddle of flexible material arranged to be interposed between said pressure applying means and the bottom of the shoe, said saddle being so 30 formed as to present toward a portion of the bottom of the shoe a face which is concave in the direction of the length of the shoe.

In testimony whereof, I, the said ERASTUS E. WINKLEY, have signed my name to this 40 specification.

ERASTUS E. WINKLEY.

In testimony whereof I, the said HERMAN A. DAVENPORT, have signed my name to this specification.

HERMAN A. DAVENPORT.
